ATTORNEYS.

UNITED STATES PATENT OFFICE.

ROBERT E. MCEDOWNEY, OF NEW MARTINSVILLE, WEST VIRGINIA, ASSIGNOR TO
NEW MARTINSVILLE GLASS MFG. CO., OF NEW MARTINSVILLE, WEST VIRGINIA, A
CORPORATION OF WEST VIRGINIA.

DESIGN FOR A POWDER-PUFF BOX OR SIMILAR ARTICLE.

Application filed September 7, 1928. Serial No. 28,067. Term of patent 3½ years.

To all whom it may concern:

Be it known that I, ROBERT E. MCEDOWNEY, a citizen of the United States, residing at New Martinsville, in the county of Wetzel and State of West Virginia, have invented a certain new, original, and ornamental Design for a Powder Puff Box or Similar Article, of which the following is a specification, reference being had to the accompanying drawing, forming part thereof, in which—

Fig. 1, is a view in perspective of the powder puff box or similar article showing my new design.

Fig. 2, is a top or plan view of a powder puff box or similar article showing my new design.

Fig. 3, is a view in elevation thereof.

I claim:

The ornamental design for a powder puff box or similar article as shown.

ROBERT E. MCEDOWNEY.
